DESIGN FOR A DICE BOX

Mortimer M. Kastner, Montreal, Quebec, Canada

Application May 11, 1945, Serial No. 119,504

Term of patent 7 years

(Cl. D34—5)

To all whom it may concern:

Be it known that I, Mortimer M. Kastner, a subject of the King of Great Britain and resident of the city of Montreal, in the Province of Quebec, and Dominion of Canada, have invented a new, original, and ornamental Design for Dice Box, of which the following is a specification, reference being had to the accompanying drawing, forming a part thereof.

In the accompanying drawing:

I claim:

The ornamental design for a dice box, as shown.

MORTIMER M. KASTNER.
